CLAIM

The ornamental design for a sauté pan, as shown and described.

DESCRIPTION

FIG. 1 is a side view of a sauté pan with a lid and handle shown in phantom;

FIG. 2 is a front view of the sauté pan shown in FIG. 1 with a lid and handle (shown in phantom);

FIG. 3 is a rear view of the sauté pan shown in FIG. 1 with a lid and handle shown in phantom;

FIG. 4 is a side view of the sauté pan shown in FIG. 1 on the opposite side to that shown in FIG. 1 with a lid and a handle (shown in phantom);

FIG. 5 is a top view of the sauté pan shown in FIG. 1 with the lid removed;

FIG. 6 is a bottom view of the sauté pan shown in FIG. 1 with a handle shown in phantom; and,

FIG. 7 is a side view of the sauté pan shown in FIG. 1 slightly tilted without a lid and a handle shown in phantom.

The features shown in phantom are for illustrative purposes only and form no part of the claimed design.
